CARBURETOR

Elmer Olson, Rochester, N. Y., assignor to General Motors Corporation, Detroit, Mich., a corporation of Delaware

Application September 23, 1950, Serial No. 186,421

7 Claims. (Cl. 261—34)

1.

The invention relates to carburetors for internal combustion engines and particularly to carburetors for automotive use. As illustrated in this application, the invention is embodied in a carburetor such as shown in applicant's copending application Serial No. 109,347, filed August 9, 1949, but the invention is applicable to any carburetor employing an accelerator pump.

The purpose of this invention is to prevent fuel being drawn into the mixture passage from the cylinder of the accelerator pump through the discharge nozzle of such pump by the suction which is maintained in the mixture passage. In accelerator pumps which are provided to supply additional fuel to enrich the mixture for purposes of acceleration, the discharge passage is frequently provided with a check valve which is normally held in closed position by a spring and which is unseated by the pressure of the pump piston on the active stroke of the latter so as to permit fuel to flow from the pump cylinder through the discharge nozzle and into the mixture passage. The spring is designed to hold the valve closed at all times except during the active stroke of the pump piston, which occurs on opening movements of the throttle, to prevent the suction maintained in the mixture passage acting to draw fuel from the pump through the discharge nozzle thereof.

Some difficulty has been encountered in devices of this kind under certain circumstances. The suction in the mixture passage becomes quite high upon occasions and if a strong enough spring is used to prevent opening of the check valve by suction under all operating conditions, it is necessary to use a spring of sufficient strength to appreciably delay the opening of the check valve by the pressure created by the pump piston on its active stroke. This results in a momentary lag in the acceleration of the engine and vehicle which is objectionable.

The primary object of the present invention is to provide means for controlling the fuel discharge passage of an accelerator pump which is effective at all times to prevent any possible discharge of fuel through such passage except during the active stroke of the pump piston, but which will permit an immediate discharge of fuel therefrom when the piston is operated on its pumping stroke with substantially no delay or lag in the fuel discharge.

According to the present invention this object is accomplished by the provision of a ball check valve which is normally held in position to close the discharge passage of the accelerator

2.

pump by a very light spring received between the ball and a piston of larger area than the ball which is slidable in a cylinder to which the suction of the mixture passage is communicated through the pump delivery nozzle. The spring exerts so little force on the ball that very little pressure will unseat the ball against the closing force of such spring. The ball and the piston are both subject to the suction of the mixture passage and this suction, of course, tends to unseat the ball. However, since the piston is larger than the ball, the suction moves the piston to collapse the spring so that a pin carried by the piston engages the ball and holds it closed. In other words, the effect of suction closes the check valve instead of opening it.

Further objects and advantages of the present invention will be apparent from the following description, reference being had to the accompanying drawings wherein a preferred embodiment of the present invention is clearly shown.

In the drawings:

Fig. 1 is a vertical section through the carburetor.

Fig. 2 is a fragmentary vertical section through the means for controlling the discharge passage of the accelerator pump.

Fig. 3 is an enlarged detail view in elevation of the piston which is shown in section in Fig. 2.

Referring to Fig. 1, the carburetor shown therein comprises three separate castings numbered 1, 2 and 3, respectively. The casting 1 is the carburetor outlet which is adapted to be connected with the intake manifold in the usual manner, the casting 2 is positioned above the outlet casting 1 and has a constant level fuel chamber 2a formed therein, while the casting 3 forms a cover for the fuel chamber and also has the air intake 4 formed therein. These three castings are separated by gaskets to form tight joints and to limit the transfer of heat between the castings as much as possible by preventing any metallic contact of the castings with each other.

In the outlet casting 1 a throttle shaft 5 is suitably journaled and secured to such shaft is the usual throttle valve 6 which is manually adjustable by means not shown to control the volume of combustible mixture which is supplied by the carburetor to the engine.

In the casting 3 a choke valve 7 is positioned and this valve is secured to a shaft 8 which is suitably mounted in the casting 3 for rotation. The choke valve in the carburetor disclosed herein is manually operated and, when the engine is operating at normal temperature, is

adapted to be positioned in wide open position so as not to restrict the quantity of air entering the carburetor, but is adapted to be closed, or partly closed, by the manual operating connections when the engine is started cold in order to facilitate starting, the position to which the choke valve is moved being dependent upon the temperature at the time of starting. The choke valve is adapted to be moved to different positions by means of the arm numbered 9 which is adapted to be operated by a connection leading to the dash which is not shown herein, but is a conventional construction. The arm 9 operates the choke valve through mechanism which need not be described herein, but is fully shown and described in the copending application above referred to. It may be said, however, that the operation of the choke valve by the arm 9 is effected through a spring 10 which holds the choke valve yieldingly closed, so that when the engine starts to run under its own power, the increase in engine suction which then occurs can pull the valve open to some extent against the force of the spring 10, so as to prevent over-choking.

In the carburetor shown herein, the choke valve is also designed to operate the throttle so as to move the throttle slightly toward open position when the choke valve is moved to its fully closed position in order that the idling speed may be somewhat increased when the choke valve is closed. This is done for the purpose of providing a somewhat faster than normal idling when the choke valve is closed at low temperatures which is desirable to prevent stalling. The operating connections between the choke valve and the throttle valve for effecting this movement are indicated generally by the reference numeral 11. Since this mechanism has nothing to do with the invention in this application, it is not illustrated in detail and will not be described, but such mechanism is fully shown and described in the aforesaid copending application.

As already indicated, air is admitted to the carburetor through the air inlet 4 and fuel is supplied to the carburetor through a main fuel nozzle 12 which terminates at the throat of a small Venturi tube 13 which, itself, terminates at the throat of a large Venturi tube 14 integral with the casting 2 and forming a part of the mixture passage which extends vertically through the carburetor. The purpose of these Venturi tubes is, of course, to increase the velocity of air flow past the end of the main fuel nozzle 12 to create a partial vacuum adjacent the nozzle outlet in the usual and well known manner. Fuel is also supplied to the intake passage by an idling fuel inlet which is not shown herein, but which terminates in an orifice communicating with the intake passage at the point adjacent and slightly posterior to the edge of the throttle valve 6 when the latter is in closed position.

Fuel is supplied to both of these fuel inlets from the fuel chamber 2a and fuel is supplied to the latter through a coupling 15 which is screwed into the casting 3 and to which a fuel supply pipe extending to the main fuel tank of the vehicle is adapted to be connected. Fuel which is supplied through the coupling 15 enters a passage 16 formed in the casting 3 and flows through a passage in a nipple 17, which is screwed in the wall of the casting 3, and communicates with the fuel bowl 2a when the parts are assembled as shown in Fig. 1. The flow of

fuel through the passage 17 into the bowl is controlled by a valve 18 which cooperates with the passage 17 and rests on one arm of a lever 19 which is pivoted on a pin 20 fixed in position in the wall of the fuel chamber 2a. The lever 19 is connected to the float mechanism which is not shown, but which is received within the chamber 2a and when the fuel level in said chamber reaches a definite height, the float lifts the lever 19 so as to close the valve 18 and cut off the flow of fuel into the float chamber in the usual way. The float mechanism is of conventional construction and has nothing to do with the invention which is claimed in this application.

Before describing the fuel passage which conveys fuel from the fuel chamber 2a to the main and idling fuel inlets, the accelerator pump will be briefly described. The specific construction of the pump, itself, constitutes no part of the present invention and may be of the same construction as shown in the aforementioned copending application. This pump includes a cylinder 25 into which fuel can flow from the fuel chamber 2a, through a passage which is not shown, and slidably in the cylinder is a pump piston 26 which is operated by a spring 27 which is received between the piston 26 and a washer 28 which engages the under side of the horizontally extending part 29 of a vertical rod 30 connected by a link 31 to the throttle operating arm 32. The part 29 projects through a slot 33 formed in a rod 34 extending upwardly from the pump piston 26.

When the throttle is opened at moderate speed, the spring 27 is compressed by the part 29 and the piston is moved downwardly through the medium of the spring. If the opening of the throttle is very rapid, the spring will be compressed enough for the part 29 to engage the bottom of slot 33 and positively move the piston downwardly during the opening of the throttle at the end of which the spring will expand, forcing the piston further in a downward direction. In other words, on sudden and relatively large opening movements of the throttle there is an immediate and positive movement of the piston 26 by the throttle operated rod 30 followed by a delayed movement which is effected by expansion of the spring.

During the described movements of piston 26, fuel is forced from the cylinder 25 through the discharge passage which leads to the mixture passage and through which the flow of fuel is controlled in a manner to be later described.

In the device disclosed herein, fuel may be conveyed from the constant level fuel chamber 2a through a fuel conduit of the same construction as that shown in the earlier copending application. This fuel conduit comprises three parts or passages which together make up a conduit shaped substantially like an inverted U, one part of the conduit being substantially vertical and extending downwardly into the float chamber from the casting 3 to which it is secured. This connects with a horizontal passage formed in casting 3, which, in turn, connects at its other end with a substantially vertical passage formed in the wall of casting 2, which leads to the idling fuel inlet, through a passage formed in the casting 1, which is not shown herein. As shown in Fig. 1, the aforementioned fuel conduit includes the vertical passage 40 formed in a member 41 which is secured in any suitable way to the casting 3 and separated therefrom by a gasket 42. The member 41 extends downwardly into cham-

ber 2a in such a way that it is entirely surrounded by fuel and not in metallic contact with any part of the chamber wall, fuel being admitted to such passage through a metering plug 43.

At its upper end, the passage 40 connects with a horizontal passage 45 formed in a rib 46 of the casting 3 which extends across the mixture passage and at its left end, as seen in Fig. 1, the passage 45 connects with the vertical passage 47 formed in the wall of casting 2, which connects at its lower end with a passage 48 which ultimately connects with the idling fuel inlet. The main fuel inlet is an orifice 49 formed in a bushing 50 which is positioned in and delivers fuel to the nozzle tube 12. Immediately above the main fuel inlet is a plug 51 having a relatively large opening 52 therein and there are two smaller openings 53 on both sides of said plug, all of which admit air to the fuel supply conduit for the purpose of effecting better fuel atomization.

From a point immediately to the left of the main fuel inlet to its point of connection with passage 47, the passage 45 is enlarged and in this enlarged part of the passage 45 is positioned a tube 54 restricted at its right end, as indicated at 55, and the passage is closed by a plug 56. The restricted end of the tube controls the supply of idling fuel and the tube also tends to minimize the formation of vapor bubbles of appreciable size in the idling mixture.

The mechanism previously described is of just the same construction as that described in greater detail in the earlier copending application and functions in the same way.

Coming now to that specific portion of the device which is the subject of the present invention, the passage 35 from the accelerator pump connects with a cylinder 60 formed in the wall of the casting 2 and connecting with this cylinder is a discharge nozzle 61 which extends into and downwardly in the mixture passage at a point above the main venturi 14 and directs the pumped fuel into the air stream and against the wall of the smaller venturi 13. The passage 35, the cylinder 60 and the nozzle 61, together, comprise the fuel discharge passage from the pump. A check valve 62 is positioned within the cylinder 60 and is normally held in position to close the passage 35 by a weak coil spring 63 which is received between the valve and a piston 64 slidable in the cylinder 60. A passage 65 connects with the top of the cylinder 60 and at its upper end is in communication with a passage 66 which may lead either to the atmosphere or the space above the fuel in the bowl 2a so that the top of the piston is subject to atmospheric pressure, or the bowl pressure. The piston has a head 67 at its upper end which has a sliding fit with the cylinder 60 and the lower part of the piston, which is of smaller diameter and cylindrical form, has a plurality of circumferential ribs 68 which also have a sliding fit with said cylinder. Spaced 180 degrees apart are vertical channels or grooves 69, as best shown in Fig. 3, which permit passage of fuel from passages 35 through the ribs 68 to the discharge nozzle 61 and through which the suction existing at the nozzle is communicated to the check valve 62 and to the space within the cylindrical body of the piston. A pin 70 is secured to the piston head and extends downwardly to a point relatively close to the check valve 62, so that a small downward movement of the piston will bring the pin into engagement with the valve to hold said valve seated.

The operation of the above described mecha-

nism should be apparent. If there is substantially no suction effective in the cylinder 60, the check valve is held closed only by the force of the light spring 63 so that if the pump is operated under such circumstances, the opening of the check valve is substantially immediate, whereby there is no appreciable delay or lag in the pump action. If suction is communicated to the cylinder 60, such suction tends to open the check valve. However, the same suction is also effective to pull the piston 64 downwardly and since the piston is larger than the check valve such piston is moved down by the suction so that pin 70 engages the check valve and holds the latter closed by a force equal to the excess of the suction effective on the larger piston over that effective on the smaller valve. It will be obvious from the foregoing that no matter what the suction in the mixture passage may be, the discharge passage 20 from the pump can never be opened thereby nor can fuel be drawn from the pump into the mixture passage by the effect of suction on the discharge nozzle.

If, at any time, the pump is operated when the check valve 62 is held closed by effect of suction as above described, the force which holds the valve closed is slight so that there is substantially no delay in the opening of the valve with respect to the action of the pump and the richer mixture necessary for satisfactory acceleration is supplied promptly and acceleration is smooth, and without the drag or hesitation that is sometimes observable in the operation of automotive vehicles.

While the embodiment of the present invention as herein disclosed, constitutes a preferred form, it is to be understood that other forms might be adopted.

What is claimed is as follows:

1. In a charge forming device for an internal combustion engine having a mixture passage, a fuel supply chamber, air and fuel inlets supplying air and fuel to said mixture passage, a throttle controlling the flow of mixture from said mixture passage, an accelerator pump having a piston operated by said throttle for supplying additional fuel for acceleration on opening movements of said throttle, said pump having a fuel discharge passage communicating with said mixture passage and subject to the suction in said mixture passage, a valve controlling the flow of fuel through the pump discharge passage, said valve being subject to the suction maintained in the mixture passage which tends to open said valve, a member movable into engagement with the valve so as to prevent opening thereof, means normally holding said member out of engagement with said valve, and means for communicating the suction of the mixture passage to said member in order to move the member into engagement with the valve when the pump is not being operated.

2. In a charge forming device for an internal combustion engine having a mixture passage, a fuel supply chamber, air and fuel inlets supplying air and fuel to said mixture passage, a throttle controlling the flow of mixture from said mixture passage, an accelerator pump having a piston operated by said throttle for supplying additional fuel for acceleration on opening movements of said throttle, said pump having a fuel discharge passage communicating with said mixture passage and subject to the suction in said mixture passage, a valve controlling said pump discharge passage, and subject to the suction in the mix-

ture passage which tends to open said valve, a member controlling the operation of said valve, a spring normally holding said valve closed and holding said member out of engagement with said valve, and means for communicating the suction of the mixture passage to said member in order to move said member into engagement with said valve so as to prevent opening of the valve when the pump is not being operated.

3. In a charge forming device for an internal combustion engine having a mixture passage, a fuel supply chamber, air and fuel inlets supplying air and fuel to said mixture passage, a throttle controlling the flow of mixture from said mixture passage, an accelerator pump having a piston operated by said throttle for supplying additional fuel for acceleration on opening movements of said throttle, said pump having a fuel discharge passage communicating with said mixture passage and subject to the suction in said mixture passage, said pump discharge passage being enlarged between the pump and the discharge end of said passage to form a cylinder, a valve positioned in said cylinder and controlling the flow of fuel through said discharge passage, a piston slidable in said cylinder and movable into engagement with said valve to hold the valve in closed position, a spring positioned between the valve and said piston and normally effective to hold the valve closed and the piston in a position where it does not engage said valve, and a suction passage connecting the space in said cylinder between the valve and piston with the mixture passage, whereby the suction in the mixture passage is effective to move the piston into engagement with said valve, so as to hold the valve closed when the pump is not being operated.

4. In a charge forming device for an internal combustion engine having a mixture passage, a fuel supply chamber, air and fuel inlets supplying air and fuel to said mixture passage, a throttle controlling the flow of mixture from said mixture passage, an accelerator pump having a piston operated by said throttle for supplying additional fuel for acceleration on opening movements of said throttle, said pump having a fuel discharge passage communicating with said mixture passage and subject to the suction in said mixture passage, said pump discharge passage being enlarged between the pump and the discharge end of said passage to form a cylinder, a valve positioned in said cylinder and controlling the flow of fuel through said discharge passage, said valve being subject to the suction maintained in the mixture passage which tends to open said valve, a piston slidable in said cylinder in response to the suction in the mixture passage and movable thereby to a position to prevent opening of said control valve in response to suction, said piston having a head of approximately the same diameter as that of the cylinder in which it slides and a smaller body portion, a circumferential rib on said body portion of substantially the same diameter as the piston head and an axial groove through said rib to permit a flow of fuel therethrough and to communicate the suction of the mixture passage to the interior of said cylinder.

5. In a charge forming device for an internal combustion engine having a mixture passage, a fuel supply chamber, air and fuel inlets supplying air and fuel to said mixture passage, a throttle controlling the flow of mixture from said mixture passage, an accelerator pump having a piston operated by said throttle for supplying

additional fuel for acceleration on opening movements of said throttle, said pump having a fuel discharge passage communicating with said mixture passage and subject to the suction in said mixture passage, said pump discharge passage being enlarged between the pump and the discharge end of said passage to form a cylinder, a valve positioned in said cylinder and controlling the flow of fuel through said discharge passage, said valve being subject to the suction maintained in the mixture passage which tends to open said valve, a piston slidable in said cylinder in response to the suction in the mixture passage and movable thereby to a position to prevent opening of said control valve in response to suction, said piston having a head of approximately the same diameter as that of the cylinder in which it slides and a smaller cylindrical body portion spaced from the wall of said cylinder, and a spring positioned within said cylindrical body portion and engaging said valve whereby said spring is normally effective to hold said valve closed.

6. In a charge forming device for an internal combustion engine having a mixture passage, a fuel supply chamber, air and fuel inlets supplying air and fuel to said mixture passage, a throttle controlling the flow of mixture from said mixture passage, an accelerator pump having a piston operated by said throttle for supplying additional fuel for acceleration on opening movements of said throttle, said pump having a fuel discharge passage communicating with said mixture passage and subject to the suction in said mixture passage, said pump discharge passage being enlarged between the pump and the discharge end of said passage to form a cylinder, a valve positioned in said cylinder and controlling the flow of fuel through said discharge passage, said valve being subject to the suction maintained in the mixture passage which tends to open said valve, a piston slidable in said cylinder in response to the suction in the mixture passage and movable thereby to a position to prevent opening of said control valve in response to suction, said piston having a head of approximately the same diameter as that of the cylinder in which it slides and a smaller cylindrical body portion spaced from the wall of said cylinder, a spring positioned within said cylindrical body portion and engaging said valve whereby said spring is normally effective to hold said valve closed, a plurality of circumferential ribs on said cylindrical body portion of substantially the same diameter as the piston head and an axial groove extending through all of said ribs to permit the flow of fuel therethrough and to communicate the suction of the mixture passage to the interior of said cylindrical body of the piston.

7. In a charge forming device for an internal combustion engine having a mixture passage, a fuel supply chamber, air and fuel inlets supplying air and fuel to said mixture passage, a throttle controlling the flow of mixture from said mixture passage, an accelerator pump having a piston operated by said throttle for supplying additional fuel for acceleration on opening movements of said throttle, said pump having a fuel discharge passage communicating with said mixture passage and subject to the suction in said mixture passage, said pump discharge passage being enlarged between the pump and the discharge end of said passage to form a cylinder, a valve of smaller size than said cylinder positioned therein and controlling the flow of fuel through said discharge passage, a piston of larger

size than said valve slidable in the cylinder and movable into engagement with the valve to hold it in closed position, a spring in said cylinder between the valve and piston, said spring being normally operative to hold the valve closed and the piston out of engagement with said valve, and a suction passage connecting the space in said cylinder between the valve and piston with the mixture passage, whereby the suction in the mixture passage is effective to move the piston into engagement with said valve, so as to hold

the valve closed when the pump is not being operated.
